POWER SYSTEM FOR FIREARMS

David C. Fletcher, Springfield, Mass., assignor to the United States of America as represented by the Secretary of the Army

Filed Dec. 7, 1956, Ser. No. 627,081

5 Claims. (Cl. 89—192)

(Granted under Title 35, U.S. Code (1952), sec. 266)

The invention described herein may be manufactured and used by or for the Government for governmental purposes without the payment of any royalty thereon.

This invention relates to firearms and more particularly to power systems for actuating the operating mechanisms thereof.

It is an object of this invention to provide a power system which is especially well-adapted for those firearms which require a long power stroke for the actuation of the operating mechanisms.

It is another object of this invention to provide a firearm power system whereby force is evenly applied to the operating mechanism of the firearm during the entire power stroke.

It is still another object of this invention to provide a firearm power system whereby the firearm operating mechanism is energized by gas pressure from an exploded cartridge indirectly so as to eliminate the impact of such gas pressure against the operating mechanism.

It is another and still further object of this invention to provide for firearms a power system by which the operating mechanism is powered by a spring which is energized by gases bled from the firearm barrel.

The specific nature of the invention as well as other objects and advantages thereof will clearly appear from a description of a preferred embodiment as shown in the accompanying drawings in which:

Fig. 1 is a longitudinal cross-sectioned view of the power system showing the parts in normal position;

Fig. 2 is similar to Fig. 1 but showing the sleeve retracted to energize the spring and latched to the cylinder for transferring the energy in the spring to the operating rod;

Fig. 3 is similar to Fig. 2 but showing the operating rod actuated by the spring to the rearward position with the latch actuated thereby to release the sleeve from the gas cylinder;

Fig. 4 is a view taken along line 4—4 of Fig. 1;

Fig. 5 is a view taken along line 5—5 of Fig. 2; and

Fig. 6 is a perspective view of the latch member.

Shown in the figures is a firearm barrel 12, a gas cylinder 14 and an operating rod 16. Gas cylinder 14 is provided with integral brackets 18 and 20 at the front and rear ends thereof, respectively, by which the gas cylinder is secured to barrel 12 and a gas port 21 through the cylinder and the barrel provides passage for gases from the bore of the barrel to a longitudinal bore 22 through the cylinder. The rear end of operating rod 16 cooperates with the firearm operating mechanism (not shown) for the actuation thereof, and the front end is slidably received by the bore 22 for longitudinal reciprocation therein between a forward and a rearward position.

The front portion of operating rod 16 is reduced in diameter, as noted at 24, and such reduced diameter portion is terminated by an annular shoulder 26 which is arranged to be disposed outside of cylinder 14 when the operating rod is in the forward position. Portion 24 is

smaller in diameter than bore 22 so that a compressible coil spring 28 may be received over such portion and within such bore. Spring 28 is adapted to store sufficient energy to operate operating rod 16 and the attached operating mechanism. An annular collar 30 is mounted on portion 24 for rearward contact with shoulder 26 to provide a seat for the rear end of spring 28. Slidably mounted on portion 24 forwardly of spring 28 is a sleeve 32 having a bore 34 with a diameter similar to that of such portion so that the sliding contact therebetween is substantially gas tight and the outside of such sleeve has substantially gas-tight sliding contact with bore 22. Annular grooves 36 and 38 are provided in the outside and the inside surfaces of sleeve 32, respectively, to assist in preventing the escape of gases by such sleeve. The rear end of sleeve 32 is in contact with the front end of spring 28 so that such spring is energized when such sleeve moves rearwardly along portion 24. The front end of sleeve 32 is reduced in diameter, as noted at 40, to form an annular shoulder 42.

A plug 44 is threadably mounted in the front end of bore 22 and provided through such plug is a relatively small passageway 46 by which the inside of cylinder 14 is vented to the atmosphere. The rear end of plug 44 is contactable by the front end of operating rod 16 to establish the forward position thereof. Fixedly mounted to the front end of operating rod 16 is a cylindrical head member 48 having a diameter similar to that of bore 22 so that the sliding contact therebetween is substantially gas tight. The front end of sleeve 32 contacts the rear end of head member 48 and such rear end is arranged to slope forwardly and outwardly from the area of contact with reduced diameter portion 40 of the sleeve to form a cam portion 50. With sleeve 32 in contact with head member 48, there is formed with reduced diameter portion 40 an annular chamber 52 which, when operating rod 16 is in contact with plug 44, receives gases from port 21 to initiate the rearward movement of such sleeve against spring 28.

Provided in rear bracket 20 is a vertically-disposed slot 54 which is introduced into such bracket laterally from the right side thereof. Such slot 54 is terminated by a semicylindrical portion 56 which has a diameter substantially similar to the outside diameter of cylinder 14 and is aligned axially therewith. Mounted in slot 54 for lateral movement therein is a latch member 58 which consists of a cylindrical portion 60 having a diameter similar to that of semicylindrical portion 56 and a radially extending lug portion 62 which is slidably received by an opening 64 through rear bracket 20 central of portion 56. Lug portion 62 extends outwardly from opening 64 and is acted on by a leaf spring 66 to bias cylindrical portion 60 out of axial alignment with cylinder 14. Provided axially through cylindrical portion 60 is a cylindrical hole 68 which is alignable with bore 22 when such cylindrical portion is in engagement with semicylindrical portion 56 and such hole has a diameter similar to bore 22 so that spring 28 and sleeve 32 are receivable thereby.

Cylindrical portion 60 is sufficiently long so that at least one coil of spring 28 is in engagement therewith as such spring moves through hole 68 and thereby such cylindrical portion is restrained in alignment with bore 22. Provided through rear bracket 20 from bore 22 is a vent port 61 whereby the gas pressure in gas cylinder 14 is vented to the atmosphere when sleeve 32 is moved rearwardly to where shoulder 42 is rearward of latch member 58. The rearward travel of sleeve 32 is limited by the solid height of spring 28 and the reduction of pressure in gas cylinder 14, due to vent port 61 being uncovered, reduces the forces against such spring before reaching solid height. When sleeve 32 is at the limit of the rearward

travel thereof, shoulder 42 is disposed rearwardly of latch member 58 so that such latch member is biasable by spring 66 out of alignment with bore 22 into engagement with reduced diameter portion 40 and so into position to be engaged by shoulder 42 during subsequent forward movement of such sleeve.

When operating rod 16 is in the rearward position thereof, head member 48 is received by hole 68. Provided on the front end of cylindrical portion 60 is an annular beveled portion 70 which extends outwardly and forwardly from hole 68 and is cammingly cooperable with cam portion 50 on head member 48 to move latch member 58 into alignment with bore 22 for the release of sleeve 32 when the operating rod 16 is in the rearward position.

Mounted on operating rod 16 rearwardly of reduced diameter portion 24 is a compressible coil spring 72 which is immovably anchored at the rear end to a portion of the firearm (not shown) with the front end seated against collar 30. Spring 72 is thereby compressed during rearward movement of operating rod 16 so that such operating rod is returnable thereby to forward position when sleeve 32 is released from latch member 58.

Operation

When a cartridge is fired in barrel 12, the gases developed from the explosion pass through gas port 21 as the bullet passes thereby. The gases pass from gas port 21 into chamber 52 to press with equal force on the rear end of head member 48 and the front end of sleeve 32. Thereby, head member 48 is held in engagement with plug 44 and sleeve 32 is moved rearwardly against spring 28 which is compressed and energized thereby as the rear end thereof is held against movement by the engagement with the immovably held operating rod 16 through collar 30 and shoulder 26.

When sleeve 32 has been moved by the rearward position thereof, vent port 61 is uncovered, permitting the gases in gas cylinder 14 to escape, and shoulder 42 is moved past latch member 58 which is thereby unblocked so as to be biased by spring 66 against reduced diameter portion 40. With the venting of the gas pressure in gas cylinder 14, the force holding operating rod 16 forwardly is released and the bias of the energy impressed in spring 28 moves sleeve 32 forwardly into contact with latch member 58 to immovably anchor the front end of the spring to gas cylinder 14. Thereby, the energy in spring 28 is transferred to operating rod 16 which is moved rearwardly overpowering spring 72 to actuate the attached firearm operating mechanism (not shown).

When operating rod 16 approaches rearward position, cam portion 50 on head member 48 cammingly engages bevel portion 70 on latch member 58 to align hole 68 with sleeve 32 for the release thereof whereby operating rod 16 is no longer movably biased by spring 28 and spring 72 is permitted to return the operating rod and sleeve 32, carried thereby, to their forward positions.

In the event gases leak by head member 48 such gases are vented to the atmosphere through passageway 46 so as not to press forwardly against such head member.

From the foregoing it is clearly apparent that there is herein provided for firearms a novel power system whereby the power stroke may be of greater length than that provided by conventional power systems because of the spring powering means and whereby an even force is applied to the firearm operating mechanism during the entire power stroke as contrasted to conventional gas and recoil actuated systems which are energized by impact blows. It is also apparent that the power system of the invention is positive in operation and simple and rugged in construction.

Although a particular embodiment of the invention has been described in detail herein, it is evident that many variations may be devised within the spirit and scope

thereof and the following claims are intended to include such variations.

1. claim:

1. A power system for a firearm having a barrel with a bore, said power system including a cylinder, an operating rod slidably mounted in said cylinder and being biased from a retracted to a normal position, a spring and a sleeve carried by said operating rod with said sleeve being slidably actuatable against said spring for the energizing thereof, a port for passing gases from the bore to said cylinder, a chamber formed between said sleeve and said operating rod in said cylinder for receiving gases from said port whereby said operating rod is held immovable in the normal position and said sleeve is moved against said spring for the energizing thereof, latch means for releasably engaging said sleeve to said cylinder to transfer the energy in said spring to said operating rod for the actuation thereof to the retracted position, and cooperating cam means on said operating rod and said latch means for disconnecting said sleeve from said cylinder when said operating rod is in the retracted position for the return thereof to the normal position.

2. A power system for a firearm having a barrel with a bore, said power system including a cylinder, an operating rod slidably received by said cylinder and being biased from a retracted to a normal position, a spring attached at one end to said operating rod, a sleeve slidably mounted on said operating rod for substantially gas-tight contact with said cylinder and said operating rod and for actuation against said spring for the energizing thereof, a head member mounted to said operating rod for engagement by said sleeve, a reduced diameter portion on said sleeve to form with said head portion an annular chamber, a gas port for passing gases from the bore of the barrel to said chamber to simultaneously hold said operating rod in the normal position and move said sleeve against said spring for the energizing thereof, latch means for releasably engaging said sleeve to said cylinder when said spring is energized, vent means for releasing the gas pressure in said cylinder when said sleeve is latched to said cylinder to permit movement of said operating rod to the retracted position by the energy in said spring, and cooperating cam means on said head member and said latch means for actuating said latch means to release said sleeve from said cylinder whereby said operating rod is permitted to return to normal position.

3. A power system for a firearm having a barrel with a bore, said power system including a cylinder, an operating rod slidably received by said cylinder for reciprocation between a retracted and a normal position, means for biasing said operating rod to the forward position, a compressible coil spring mounted on said operating rod, means for anchoring the rear end of said spring to said operating rod, a sleeve slidably mounted on said operating rod for actuation against said spring for the energizing thereof, said sleeve having substantially gas-tight sliding contact with said operating rod and said cylinder, a reduced diameter portion on the front end of said sleeve, a head member mounted to the front end of said operating rod for substantially gas-tight sliding contact with said cylinder and being engageable by said sleeve through the bias of said spring, a plug mounted in the front end of said cylinder for engagement by said head member when said operating rod is in normal position, a gas port leading from the bore of the barrel to said cylinder, a chamber formed by said reduced diameter portion between said sleeve and said head member for receiving the gases from said gas port to forcibly hold said head member in contact with said plug and move said sleeve against said spring for the energizing thereof, latch means for releasably engaging said sleeve to said cylinder to transfer the energy in said spring to said operating rod for the actuation thereof to the retracted position, port means through said cylinder for

venting the gas pressure therefrom to release said operating rod for movement to the retracted position by the energy in said spring when said sleeve is latched to said cylinder, and cooperating cam means on said head member and said latch means for disengaging said sleeve from said cylinder when said operating rod is in the retracted position.

4. The device of claim 3 wherein said latch means includes an annular shoulder provided on said sleeve, a cylindrical latch member provided with an axial hole therethrough for slidably receiving said operating rod and said sleeve, slot means in said gas cylinder for mounting said latch member for transverse movement relative to said sleeve to releasably engage said annular shoulder when said spring is energized, and spring means for biasing said latch member into position to be engaged by said annular shoulder and wherein said cam means engageably cooperates with said latch member to disengage said latch member from said annular shoulder when said operating rod is in the retracted position.

5. A power system for a firearm having a barrel with a bore, said power system including a gas cylinder having communication with the bore, an operating rod mounted for slidable reciprocation in said gas cylinder, a com-

pressible coil spring carried by said operating rod and anchored at one end thereto, means actuatable by gases bled from the bore to said gas cylinder for compressibly energizing said spring, a head member disposed on said operating rod for cooperation with the gases bled to said cylinder to hold said operating rod against displacement during the compression of said spring, and means for connecting the opposite end of said spring to the gas cylinder after said spring is compressed and the gas pressure is relieved in said gas cylinder for transferring the energy of said compressed spring to said operating rod for actuation thereof.
